UNITED STATES PATENT OFFICE

HORACE E. SMYTHE, OF PITTSBURGH, PENNSYLVANIA, ASSIGNOR TO THE S. R. SMYTHE COMPANY, OF PITTSBURGH, PENNSYLVANIA, A CORPORATION OF WEST VIRGINIA.

GAS-PRODUCER.

1,088,799.

Specification of Letters Patent.

Patented Mar. 3, 1914.

Application filed April 24, 1913. Serial No. 763,271.

To all whom it may concern:

Be it known that I, HORACE E. SMYTHE, a citizen of the United States, residing at Pittsburgh, in the county of Allegheny and 5 State of Pennsylvania, have invented new and useful Improvements in Gas-Producers, of which the following is a specification.

My invention relates to gas producers of the revolving inclined type.

10 The object of this invention is to provide a revolving inclined gas producer with improved means for automatically feeding the fuel to the same and in uniformly distributing the fuel therein.

15 Another object is to provide improved means for breaking up or stirring the fuel, preferably at the point where the blast comes in contact with the fuel so that a uniform fire is maintained.

20 Another object is to provide a construction whereby the gases will pass through the incandescent ashes thereby consuming the soot and converting the tar into gas.

Other objects will appear hereinafter.

25 Referring to the accompanying drawings, the figure is a vertical longitudinal section through an apparatus involving my invention.

30 On the drawings, 1 represents the inclined producer shell or body having the preferably cylindrical portion 2 provided at each end with an annular bearing 3 surrounding the portion 2 and resting on the anti-friction rollers 4. The rollers 4 are 35 supported in the housings 5 resting on suitable foundations. The annular rack 6 surrounds the body portion 2 between the bearings 3, the teeth of the rack meshing with the pinion 7 on the shaft 8 driven from any 40 suitable source of power. The shell 1 is inclined or tapered from the portion 2 to the contracted neck portion 9 which is arranged to discharge the ashes and such burning fuel as may be mixed therewith 45 into the ash-pit 10.

50 11 represents the gas off-take chamber which has its lower end below the level of the water in the ash-pit so as to provide a water-seal. The chamber 11 is provided with an opening to receive the neck 9 of the shell, there being a packing 12 around the neck and within the said opening in the chamber 11.

12' is a passage for the circulation of water to keep the adjacent parts cool.

55

The front wall of the chamber 11 is interrupted below the surface of the water in the ash-pit so that the ashes may be removed from beneath the chamber. I have shown no means for removing the ashes but 60 any well known device or apparatus may be employed for this purpose.

The chamber 11 communicates at its upper side with the gas off-take passage 13 from which the gas passes to any suitable 65 receptacle or apparatus for further treatment, there being a gate or valve 14 at the top of the chamber 11 for cutting off communication between the chamber 11 and the passage 13.

70

The upper end of the producing shell is provided with an opening in line with the axis of the producer. Within this opening I place the cylindrical fuel feeding pipe 15 which communicates at its upper end with 75 the vertical hopper 16.

17 represents an inclined shaft which lies in the line of the axis of the producer and of the pipe 15 and has one bearing at 18 in the side of the hopper and another bearing 80 at 19 inside of the upper end of the portion 2 of the shell. The shell is provided with inwardly extending arms 20 which support the bearing 19. The shaft 17 is provided with a bevel gear 21 which meshes with the pinion 22 85 on the driving shaft 23. The shaft 17 has the spiral conveying screw 24 secured thereto so that as the shaft 17 is revolved the fuel which passes into the upper end of the feed-pipe 15 will be forced by the feed-screw into 90 the upper end of the producer shell.

The shaft 17 is hollow from end to end and has its outer or upper end provided with a closure 25. This closure is provided with an inwardly tapered opening to receive a 95 correspondingly shaped hollow fitting 26 into which steam or air or both is fed by the pipe 27. The lower end of the hollow bearing 17 terminates below the arms 20 and is provided with a nozzle 28 which is preferably somewhat larger than the shaft 17 and is provided with openings extending in various directions so that the air or steam may reach practically all the fuel surrounding the nozzle. This nozzle preferably rotates 100 with the shaft and may be cylindrical with 105

a bulging lower end or it may have various other shapes. For example, the cylindrical portion of the nozzle may be a hexagon or the lower part of the nozzle may be pyramidal.

The shell 1 and the shaft 17 are kept continually turning. The shell may turn in the same direction as the shaft or in the opposite direction. The fuel from the hopper 10 16 is continuously fed by the feed-screw 24 into the shell and at the same time air, steam or both are forced through the pipe 27, the hollow shaft 17 and the nozzle 28 into the burning incandescent fuel within the shell. 15 The rotation of the shell and the shaft 17 causes the fuel to be broken up evenly around the nozzle all the time so that the fuel is uniformly supplied in every direction with the steam, air, or both. The feed-screw 20 maintains a practically solid fire-bed and aids to force the ashes out through the neck 9 of the shell into the ash-pit and a portion of the chamber 11 above the ash-pit. The blast from the pipe 27 forces the gases within 25 the shell to pass out through the incandescent fuel and ashes in chamber 11 and behind the same, thereby causing the soot to be consumed and the tar to be converted into gas. The gas practically free from 30 soot and tar passes from the chamber 11 into the passage 13, from which it may pass to any suitable apparatus for further treatment or to a receptacle or tank. By rotating the shell and the shaft 17 at suitable 35 speeds the charge in the shell can be maintained in substantially the same condition and the fuel can be evenly distributed and broken up and the blast given uniform free access to the fuel. At the same time ashes 40 can be uniformly discharged from the neck 9.

It will be observed that the shell 1 is inclined so that the fuel when fed into the same is forced against the fuel previously 45 fed, so that the feed-screw constantly keeps the charge in the shell uniform as to quantity and pressure and assists in causing the charge to pass through the shell.

I do not desire to be limited to the pre-

cise combinations and details shown and described but reserve the right to modify the same within the scope of the appended claims.

I claim—

1. In a gas producing apparatus, an inclined rotary shell, a hopper, a shaft extending axially into the upper end of the shell, a conveyer on the shaft arranged to convey fuel from the hopper into the upper end of the shell, means for supplying the said hollow shaft with a blast of air, steam or both, a blast distributing nozzle secured to the lower end of the shaft, and means for rotating the shaft in one direction and the shell in the same or opposite direction. 60

2. In a gas producing apparatus, an inclined rotary shell, a hopper, a cylindrical passage between the hopper and the upper end of the shell, an inclined hollow shaft extending through the said passage and provided with the feed-screw, means for supplying the hollow shaft with a suitable blast, and means for rotating the shaft, the shell being inclined at such an angle that the feed-screw forces the fuel continually 75 against the fuel previously fed into the shell. 75

3. In a gas producing apparatus, an inclined rotary shell, a rotary shaft extending into the upper end of the shell and arranged in axial alinement therewith, and a fuel 80 agitating device on the lower end of the shaft.

4. In a gas producing apparatus, an inclined rotary shell, a hollow rotary shaft extending into the upper end of the shell and arranged in axial alinement therewith, a hollow fuel agitating device secured to the lower end of the shaft and provided with blast distributing openings, and means for providing the hollow shaft with a suitable 90 blast. 85

Signed at Pittsburgh, Pa., this 22nd day of April, 1913.

HORACE E. SMYTHE.
